DESIGN FOR A WORK SUIT

J. Morgan Fauth, New York, N. Y.

Application October 5, 1942, Serial No. 108,437

Term of patent 3½ years

To all whom it may concern:

Be it known that I, J. Morgan Fauth, a citizen of the United States of America, residing in New York city, county of New York, and State of New York, have invented a new, original, and ornamental Design for a Work Suit, of which the following is a specification, reference being had to the accompanying drawing, forming part thereof.

Fig. 1 is a front view of a work suit showing my new design.

Fig. 2 is a rear view thereof.

I claim:

The ornamental design for a work suit, substantially as shown.

J. MORGAN FAUTH.
